UNITED STATES PATENT OFFICE.

ADOLPH F. GALL, OF WEST ORANGE, NEW JERSEY, ASSIGNOR, BY MESNE ASSIGNMENTS, TO NEW JERSEY PATENT COMPANY, OF WEST ORANGE, NEW JERSEY, A CORPORATION OF NEW JERSEY.

KINETOSCOPE.

1,117,659.

Specification of Letters Patent.

Patented Nov. 17, 1914.

Application filed June 5, 1909. Serial No. 500,417.

To all whom it may concern:

Be it known that I, ADOLPH F. GALL, a citizen of the United States, and a resident of West Orange, in the county of Essex and State of New Jersey, have made a certain new and useful Improvement in Kinetoscopes, of which the following is a description.

My invention relates to kinetoscopes and the object thereof is to provide simple and efficient means for protecting the film against the possibility of ignition from the heat of the source of light of the machine, and novel means for latching the same in open position.

More specifically, my invention comprises a door provided with the usual projection aperture and an auxiliary hinged screen or film protecting device below the said door for protecting that portion of the film which extends below the bottom of the door against the possibility of burning. The screen is provided with means coacting with the door when both are in open position to latch the same in such position, so that the screen is unlatched when the door is closed. As the screen is provided with suitable means as a spring for closing the same when it is otherwise free to close, and as the door must be closed in order to operate the machine, it is evident that by my invention a device is provided whereby an operator is prevented through carelessness or indifference from leaving the lower film protecting screen in open position. Preferably, the door carries an upper film protecting screen above the same, so that in a device constructed according to my invention, the film is protected against the heat of the lamp throughout its entire passage through the machine.

Other objects reside in the construction of parts and combinations of elements, all as hereinafter described and more particularly pointed out in the appended claims.

Reference is hereby made to the accompanying drawings forming part of this specification, in which corresponding parts are indicated throughout by the same reference characters, and in which—

Figure 1 is a rear elevation of the head of a kinetoscope embodying my invention, the film protecting door and screen being shown in closed position; Fig. 2 is a side elevation of the same looking from the right in Fig.

1; Fig. 3 is a view similar to Fig. 2, the door and screen referred to being shown in open position.

Referring to the drawings, the kinetoscope head 1 is provided with a door 2 which is provided with a film protecting fire screen 3 protecting the projection aperture in the said door and designed only to open to expose the film through said aperture when the machine is in operation and the film passing said opening at a proper speed. This device may be of any approved character, and I have shown the same as the automatic fire screen described and claimed in my Patent No. 998,571 dated July 18, 1911, for automatic film protecting screens for kinetoscopes. The door 2 is pivoted at its rear edge on the vertical pin 4, and is provided at its front edge with a locking device of any approved character, the device illustrated consisting of a vertical slide 5 carrying the latch 6, the said latch co-operating with a projection on the frame of the machine to secure the door in closed position, and the said slide 5 being provided with a thumb piece 6' for raising the slide to unlatch the door. The door is also provided with the usual springs 7 for tensioning the film and the rollers 8 coacting when the door is closed with feeding devices in the machine, the door also carrying the other usual parts. The door 2 is also preferably provided with an upwardly projecting film protecting screen 9 carried by the door and extending above the same to protect the upper portion of the film, and a downwardly projecting film protecting member 10 depending from said door.

The film protecting screen 11 is provided below the door 2, the said screen being hinged on the vertical pin 12 at the rear edge of the screen, suitable means being provided for automatically closing the screen 11, as the spiral spring 13, which is shown as coiled about the pin 12 and so arranged as to force the screen 11 into closed position. Thus the screen 11 is biased into closed or film protecting position. The screen 11 is formed to overlap the lower edge of the portion 10 of the door 2, the upper edge of screen 11 being curved toward the front of the machine, as indicated, to rest against the rear surface of the portion 10 of the door 2 when the screen and door are closed.

The upper edge of the screen 11 is provided with a notch 14 shaped as indicated in the drawings, the result of this construction being that when the door and screen 11 are 5 opened for the purpose of threading a film through the machine, or for any other purpose, the front edge of the portion 10 of the door 2 may be placed within the notch 14. As screen 11 has a constant tendency to 10 close, due to the action of spring 13, the edge of notch 14 constantly presses against the front edge of door 2, binding the parts firmly in open position, since the notch 14 is so positioned that the edge of door 2 only 15 enters the same when the door is in such position that the pressure of notch 14 upon the edge of the same is exerted in a plane parallel to the surface of the door in such position. Furthermore, notch 14 is so 20 shaped as to hold door 2 against closing while the edge thereof is retained within the notch. To close the parts, the screen 11 is pushed farther back a small distance, whereupon door 2 is free to close, screen or shield 25 11 thereafter closing automatically as soon as it is allowed to do so.

It is obvious that various modifications may be practised in my invention without departing from the spirit thereof. For example, it is evident that the position of the co-acting latch members on the screen and door might be interchanged with similar results, or that a screen similar to screen 11 might be independently mounted above door 30 2 with similar latching means to that described.

Having now described my invention, what I claim and desire to protect by Letters Patent is as follows:

40 1. In a kinetoscope, the combination with a film protecting door having a projection aperture, of a movable film protecting screen overlapping the said door, means tending to close said screen, and means for 45 latching said door and screen in open position unlatched by the closing of the said door, substantially as described.

2. In a kinetoscope, the combination with a film protecting door having a projection 50 aperture, of a movable film protecting screen, means tending to close said screen, said door and screen being arranged one above the other, said screen being provided with means co-acting with said door when 55 the latter is open for holding said screen in open position.

3. In a kinetoscope, the combination of 60 two film protecting members, one above the other, the lower member at its upper edge overlapping the lower edge of the upper member, and hinged mountings for said members at the rear edge of each, said lower member being provided on its upper edge with a notch for engaging the front edge of

said upper member when both are in open 65 position for maintaining the same in such position, substantially as described.

4. In a kinetoscope, the combination of two film protecting members, one above the other, each pivoted at its rear edge to a vertical pin, said pins, one of said members at one of its horizontal edges overlapping the adjacent horizontal edge of said other member, means tending to close said first mentioned member, said first mentioned member 70 being provided on its said horizontal edge with a notch for engaging the front edge of said other member when both are in open position for maintaining the said first mentioned member in open position only so long 75 as the other member is open, substantially as described.

5. In a kinetoscope, the combination of a film protecting door, a screen carried by said door above the same, and an independently 80 hingedly mounted film protecting screen below said door, said door and film protecting screen being so arranged that the opening of one will positively effect the opening of the other, substantially as described.

6. In a kinetoscope, the combination of a film protecting door and an independently mounted hinged film protecting screen below said door, said door and film protecting screen being so arranged that the opening of one will positively effect the opening of the other, substantially as described.

7. In a motion picture machine, a frame, mechanism carried by said frame for feeding a film, a film protecting door having a light aperture, means for guiding said film across said aperture, a shield for closing said aperture, and an independently mounted movable member for covering the film beneath said door, said door and member being 105 so arranged that the opening of one will positively effect the opening of the other, substantially as described.

8. In a motion picture machine, a frame, mechanism carried by said frame for feeding a film, a film protecting door having a light aperture, a shield for closing said aperture, and a member hinged to the frame for covering the film beneath said door, said door and member being so arranged that the 110 opening of one will positively effect the opening of the other, substantially as described.

9. In a kinetoscope, the combination of a film protecting door, a screen carried by said 115 door above the same, and an independently mounted film protecting screen below said door and biased into film protecting position, substantially as described.

10. In a kinetoscope, the combination of a 120 film protecting door, a screen carried by said door above the same, an independently mounted film protecting screen below said

- door, and means tending to move the independently mounted screen into film protecting position, substantially as described.
11. In a kinetoscope, the combination of a film protecting door, and an independently mounted film protecting screen below said door and biased into film protecting position, substantially as described.
12. In a kinetoscope, the combination of a film protecting door, an independently mounted film protecting screen below said door, and means tending to move the independently mounted screen into film protecting position, substantially as described.
13. In a motion picture machine, a frame, mechanism carried by said frame for feeding a film, a door having a light aperture, means for guiding said film across said aperture, a movable shield for covering the film beneath said door, and means tending to move said shield into film covering position, substantially as described.
14. In a motion picture machine, a frame, mechanism carried by said frame for feeding a film, a door having a light aperture, a shield for closing said aperture, and a shield hinged to the frame for covering the film beneath said door, said hinged shield being biased into film covering position, substantially as described.
15. In motion picture apparatus, the combination of a pair of movably mounted film protecting members arranged adjacent each other, one of said members being adapted to directly coact with the other of said members, when the latter is open, for maintaining both of said members in open position, substantially as described.
16. In a motion picture machine, the combination of two independently mounted film protecting members disposed adjacent each other and movable in the same direction to open position, said members being so arranged that the opening of one will positively effect the opening of the other, substantially as described.
17. In a motion picture machine, the combination of two independently mounted movable film protecting members disposed one above the other, said members being so arranged that one of said members when opened will act directly upon the other member to thereby positively effect the opening of the latter, substantially as described.

This specification signed and witnessed this 4th day of June, 1909.
